ABSTRACT: A rocket motor for steering a ballistic missile during the powered stage of its flight. The motor, which is of the liquid propellant rocket type, is affixed to the forward end of the ballistic missile and includes a plurality of combustion chambers having angularly oriented plug nozzles. When it becomes necessary to change the course of the missile, fuel and oxidizer are introduced into one or more of the combustion chambers, to cause the resultant thrust to accomplish the desired change of course.

1
UNIFIED ROCKET CONTROL

BACKGROUND OF THE INVENTION

This invention relates to the art of steering of ballistic type missiles and, more particularly, to a rocket motor of the liquid propellant type having a plurality of combustion chambers for steering such a missile during the powered portion of its flight.

The term "ballistic missile," as used herein, is intended to mean any missile, including a multiple-stage one, which is launched, follows a selected course, is powered to the desired velocity and desired altitude, and which, during the non-powered phase, follows a free-flight path consisting essentially of a ballistic trajectory, irrespective of whether the terminal portion of the flight is guided or not.

Steering of a ballistic type missile, during the powered portion of its flight, has been attempted in many ways. All of them are intended primarily to prevent undesirable roll, pitch, and yaw, and, thereby, to provide stabilization of the missile from launch of the entire missile, *i.e.*, stages and payload or warhead, until entry of the payload or warhead into the ballistic trajectory.

Some of the methods and apparatuses include, but are not limited to: (a) fins, usually in pairs in cruciform arrangement; (b) movable nozzles which can be swiveled to redirect the jet thrust; (c) exhaust vanes, *i.e.*, surfaces which are installed directly in the exhaust path of the jet stream; (d) air deflector controls, *i.e.*, devices, partially or wholly internal to the missile, to modify the air flow pattern about the missile; and (e) gimballed power plants to reorient the thrust.

All of the above-mentioned methods and apparatuses, as well as others known but not mentioned herein, have two things in common. Firstly, they are used, or are intended for use, at or near the aft end of the missile. This results in an undesirably shorter, relatively speaking, lever arm to the center of mass of the missile as a whole. Secondly, all add weight and complexity to the missile. The added weight results in a geometric increase of the thrust required to propel the missile. The added complexity increases the probability of the unreliability of the missile as a whole. In addition, some of the steering methods and apparatuses may create unique peripheral problems. For example: Where movable nozzles are used, premature erosion may be introduced, and added to, existing problems.

All of these problems are multiplied and magnified by the fact that, as the stages of the missile increase in number, each stage is provided with an independent steering means, while the sole guiding means remains at the payload or warhead end of the missile.

This invention avoids all of these disadvantages, and obviates these problems, by providing a simple, highly reliable, unified steering apparatus for the entire missile, and positioning said steering apparatus at the payload or warhead, not aft, end of the missile.

In addition, this invention further advances the state-of-the-art by providing aerodynamic protection for the nose cone portion of the payload or warhead, by permitting aerodynamic heating of the propellant used in the invention, by allowing the use of propellant in the invention for forward acceleration when any of the propellant is not needed for steering, and by increasing the length of the lever arm to the center of mass of the missile.

SUMMARY OF THE INVENTION

This invention, a rocket motor of the liquid propellant type, permits the steering of ballistic missiles.

An object of this invention is to provide an efficient and reliable method and apparatus for steering ballistic missiles.

Another object of the invention is to provide a more simple and more economical, method and apparatus for steering ballistic missiles.

A further object of this invention is to permit unified steering for the entire ballistic missile, rather than independent steering for each stage.

2

A still further object of the invention is to provide a lightweight apparatus for steering ballistic missiles, thereby resulting in a significant saving in weight over other state-of-the-art steering apparatuses.

5 Other additional, and equally important, objects of this invention are the mechanical advantage of a longer lever arm to the center of mass of the ballistic missile, aerodynamic protection for the nose cone proper of the missile, aerodynamic heating of the propellant in the invention, and the lack of consumption of thrust from the main operating engine of the ballistic missile.

10 These, and still other, objects of the invention will become readily apparent after a consideration of the description of the invention and of the drawings.

15 DESCRIPTION OF THE DRAWINGS

FIG. 1 is a side elevation view of a multiple-stage ballistic missile in a ready-for-launch attitude, with a schematic representation of the invention in position and ready for use, at the forward end of the missile.

20 FIG. 2 is a side elevation view, schematic in form, partially in vertical cross section and fragmented in part, of the principal components of the invention, with the said invention in position on the nose cone or payload of the missile.

25 DESCRIPTION OF THE PREFERRED EMBODIMENT

With reference to FIGS. 1 and 2, wherein the same components are similarly numbered, the invention, a liquid propellant rocket motor 20, is attached (by means not shown) to the forward end, *i.e.*, the nose cone 11, of ballistic type missile 10.

In FIG. 1, missile 10 is shown, as a matter of preference, as a multiple-stage one. Also shown is the center of mass 12 of missile 10.

30 With reference to FIG. 2, liquid propellant rocket motor 20 has two separate compartments, one 21 is for the fuel and the other 22 is for the oxidizer. The wall 23 which separates these compartments 21 and 22 contains a valve 24 for metering the desired quantity of the fuel and of the oxidizer into any one or more of the four combustion chambers 25 for ultimate expulsion through throats 26, which are equipped with plug nozzles which are permanently rearwardly oriented at approximately 45° to the axis of missile 10.

40 MODE OF OPERATION OF THE EMBODIMENT

When it becomes necessary to change the course of missile 10, fuel, such as hydrazine, from compartment 21, and an oxidizer, such as hydrogen peroxide, from compartment 22, are introduced by suitable remote means, such as a command signal from a ground-based station, into one or more of combustion chambers 25 necessary to accomplish the change in course. The propellants combust spontaneously and the generated thrust, or reoriented thrust if some of chambers 25 are already firing, changes the course of missile 10 to the desired one.

When missile 10 has reached the end of the powered phase of its flight, and is about to enter the free-flight ballistic trajectory portion of its flight, rocket motor 20 is separated, by suitable remote means, from the nose cone 11 and, simultaneously, all four combustion chambers 25 are fired to assist in the separation.

60 It is to be noted that, although rocket motor 20 described in the preferred embodiment is of the liquid propellant type, a rocket motor of the hybrid type, may be used.

Further, although rocket motor 20 is described, in the preferred embodiment, as having four combustion chambers 25, there may be more, or less, of such chambers 25 in a particular embodiment to achieve the same purpose.

70 While there has been shown and described the fundamental features of our invention, as applied to a preferred embodiment, it is understood that various substitutions and omissions, such as described above, may be made by those skilled in the art without departing from the spirit of the invention.

75 We claim:

1. The method of steering a missile of the ballistic type comprising the steps of:

- a. mounting a detachable multiple chamber rocket motor on the forward portion of the ballistic missile;
  - b. firing at least one chamber of said multiple chamber rocket motor, to accomplish on course positioning of the ballistic missile during the powered portion of its flight; and
  - c. detaching said multiple chamber rocket motor when the ballistic missile enters the ballistic trajectory portion of its flight.
2. The method, as set forth in claim 1, wherein the multiple chamber rocket motor is of the liquid propellant type.
3. The method, as set forth in claim 1, wherein the multiple chamber rocket motor is of the hybrid propellant type.
4. A rocket motor for steering a missile of the ballistic type, comprising:
- a. a casing configured at the aft end to abut upon the nose cone of the missile and detachably mounted upon the

nose cone;

- b. a compartment, within said casing, to hold a liquid rocket fuel;
- c. a compartment, within said casing, to hold a liquid rocket oxidizer;
- d. a plurality of combustion chambers, within said casing, and equally spaced from each other;
- e. means, leading from said liquid fuel compartment to said combustion chambers, for metering said liquid fuel to said combustion chambers;
- f. means, leading from said liquid oxidizer to said combustion chambers, for metering said liquid oxidizer to said combustion chambers;
- g. nozzles, permanently rearwardly oriented at approximately 45° to the axis of the missile, leading from said combustion chambers to the exterior of said casing; and
- h. means for detaching, by remote control, said detachably mounted casing and its contents.
